UNITED STATES PATENT OFFICE.

JOHN WHITEHEAD, OF CHICAGO, ILLINOIS, ASSIGNOR TO THE PAYSON MANUFACTURING COMPANY, OF CHICAGO, ILLINOIS, A CORPORATION OF ILLINOIS.

MECHANISM FOR OPERATING WINDOWS IN SERIES.

1,075,618.

Specification of Letters Patent.

Patented Oct. 14, 1913.

Application filed October 3, 1910. Serial No. 584,986.

To all whom it may concern:

Be it known that I, JOHN WHITEHEAD, a citizen of the United States, residing at Chicago, in the county of Cook and State of Illinois, have invented a certain new and useful Improvement in Mechanism for Operating Windows in Series, of which the following is a full, clear, concise, and exact description.

0 My invention relates to mechanism for simultaneously operating a series of windows. Its object is to obtain a strong, rigid and direct control of a series of vertically or horizontally pivoted windows with a minimum amount of frictional and torsional stress.

My invention comprises one or more pairs of pivoted arms, each pair so interconnected that motion communicated to one arm will thereby be communicated to the other, means whereby the relation of said arms is adjusted, and means actuated by said arms for opening or closing the several windows.

The several novel features of my invention may be more readily understood by reference to the accompanying drawings which show the preferred embodiment of my invention as applied to horizontally pivoted window sashes.

30 In said drawings, Figure 1 is a horizontal section through a series of windows, showing the operating mechanism in plan, adjusted to hold the windows closed; Fig. 2 is a similar view, showing the operating mechanism adjusted to hold the windows in open position; Fig. 3 is a central, vertical section through one of the windows, showing the closed and the open position of the window in full and in dotted lines, respectively; and Figs. 4 and 5 are side and end elevations respectively of the mechanism by which the operating cable is actuated.

Similar characters of reference refer to similar parts throughout the several views.

45 For the purpose of illustrating my invention, I have shown a series of swinging window-sashes 1, 2, 3, horizontally pivoted between the successive window jambs 4. Between the successive windows is mounted a series of pairs of arms 5, 6, each pair of arms being pivoted to swing in a horizontal plane upon the pivots 10, 10 upon a bracket 7, which bracket may be secured to the window jamb 4. The pivoted ends of said arms 5, 6 are geared together, they being pro-

vided, for example, with intermeshing, segment-gears 11, 11. The outer or free end of the arms 5, 6 have pivotally connected thereto the brace rods 8, 8, respectively, each of said brace rods being also pivotally connected, as at 9, in some suitable manner to the frame of an adjacent window-sash. Each bracket 7 is provided with a pulley-frame 12 in which is journaled two guide-pulleys 13, 13 over which the endless operating cable 14 runs. An operating rod 15 connects the arm 5 with the operating cable 14, said rod being pivoted at one end to said arm and at the opposite end to a sleeve 16 clamped about said cable.

The endless cable 14 may be mounted in any suitable manner that will provide means by which it may be operated to transmit motion to the rod 15. In the drawings such cable is shown as carried by a grooved pulley 17 journaled in the pulley-frame 18 mounted upon the jamb 4 of the first of the series of windows. Secured upon the axle of the pulley 17 is a gear wheel 19 which meshes with a worm 20 provided upon the axle of the pulley 21. Extending down from the pulley 21 are the opposite ends of a chain 22. It is obvious, therefore, that by pulling upon one or the other end of the chain 22 motion may be transmitted through the pulley 21, worm 20, gear wheel 19 and pulley 17 to the cable 19.

The position which the operating apparatus assumes when the windows are in their closed position is shown in Fig. 1. Upon pulling down upon one end of the chain 22, the operating cable 14 carries the sleeve 16 nearer to the bracket 7, thus, through the operating rod 15, swinging the arm 5 away from the arm 6. Since the two arms 5 and 6 are geared together, they will be swung outwardly from each other, and hence the rods 8, 8 will be moved into position to swing the windows open upon their horizontal pivots. By pulling upon the opposite end of the chain 22, the operation of the apparatus may be reversed to wholly or partly close the series of windows.

What I claim is:

1. As an article of manufacture, the combination with a bracket, of two arms pivoted thereon, said arms being normally nearly parallel and provided with intermeshing, segment-gears, brace rods pivoted to the free ends of said arms, and an operat-

105

110

ing rod pivoted to one of said arms, whereby both of said arms may be operated by a movement of said rod transversely with respect to the normal position of said arms, 5 said operating rod at its free end being provided with means for securing the same to an operating cable.

2. The combination with two windows provided with swinging sashes, of a bracket 10 mounted between said windows, arms pivoted upon said bracket, said arms projecting substantially at right angles to said windows and being provided with inter-

meshing, segment-gears, a brace rod extending from the free end of each of said rods to the corresponding window-sash, an operating rod secured to one of said arms, a cable to which said operating rod is connected, and means for operating said cable.

In witness whereof, I, hereunto subscribe 2 my name this 30th day of September, A. D., 1910.

JOHN WHITEHEAD.
